UNITED STATES PATENT OFFICE.

VICTOR LINDBERG, OF FAIRPORT HARBOR, OHIO.

LIFE-BOAT.

1,058,609.

Specification of Letters Patent.

Patented Apr. 8, 1913.

Application filed July 20, 1912. Serial No. 710,702.

To all whom it may concern:

Be it known that I, VICTOR LINDBERG, a citizen of the United States, residing at Fairport Harbor, in the county of Lake and 5 State of Ohio, have invented new and useful Improvements in Life-Boats, of which the following is a specification.

This invention is an improved life boat for use on vessels and consists in the construction, combination and arrangement of 10 devices hereinafter described and claimed.

One object of my invention is to provide an improved life boat of novel form which is practically unsinkable and which can not 15 be swamped or overturned by a heavy sea.

Another object of my invention is to provide improved means for releasing the life boat from the supporting skids.

In the accompanying drawing:—Figure 20 1 is partly a side elevation and partly a transverse sectional view of a life boat constructed in accordance with my invention, showing the same in place on supporting skids. Fig. 2 is a horizontal sectional view 25 of the same.

The hull 1 of my improved life boat is circular, has a flat bottom 2 which is also circular and is of less diameter than the hull and is arranged concentrically with reference thereto, there being an annular overhang 3 above the bottom which connects the same to the sides of the boat. The top 4 of the boat is substantially semi-spherical in form and is flattened on its upper side to 35 provide a circular concentrically arranged deck 5 which is preferably provided with a rail 6, as here shown.

My improved life boat is preferably made of iron or steel but may be made of any 40 other suitable material. The top 4 of the boat is provided with window ports 6' and with hinged lights 7 to close the said ports, screws 8 being provided to securely fasten the lights in a closed position and the hinged 45 lights being provided with suitable packing 9 to effect water-tight joints around the sides of the window ports. These window ports provide means for entering and leaving the life boat, when the lights are open, and to facilitate entry into the boat through 50 the window ports, the top of the boat being provided on its outer side with rungs 11 which are arranged below the window ports and of which any suitable number may be 55 provided.

Owing to the shape of my improved life

boat, the same, when afloat and when the lights are closed, is absolutely tight against the entrance of water and, hence, the boat can not be overturned or sunk in a heavy 60 sea nor can it be drawn under by the suction of a sinking vessel. At the center of the top of the boat is a ventilating funnel 12 which is provided with a cowl 13 to prevent the entrance of spray. Below the ventilating 65 funnel is a tank 14, which is held in place by supports 15 and is open at its upper side. In the event that spray should enter the ventilating funnel, it will be caught in this tank and prevented from wetting the 70 interior of the boat. On the overhang 3 are seats 16 which are arranged radially and extend entirely around the boat and each of these is provided with a hinged back 17 which may be lowered in order to convert 75 the seat into a couch. Owing to the circular shape of the boat and the arrangement of the seats on the overhang, maximum seating capacity is secured, so that a comparatively small life boat constructed in accordance 80 with my invention will suffice for a considerable number of persons. The life boat is preferably equipped with a provision chest 18 and with a fresh water tank 19, for the subsistence of the passengers and is 85 also provided with a pump 20 by means of which any water that may leak in may be disposed of, the pump being here shown as provided with an operating handle or lever 21 and as provided with an intake pipe 22 90 which leads to a point near the bottom of the boat and an outlet pipe 23 which discharges through one side of the top of the boat. The inlet pipe is provided with a valve 24. A drain pipe 25 leads downwardly from the tank 14 95 to the pump and has a valve 26. Hence, the pump may be used for pumping out water which may leak into the boat and may also be used for pumping out water which may accumulate in the spray receiving tank 14. 100 A vertical tube 27 extends up through the deck 5 and is open at its upper and lower ends. A flag staff 28 for a signal or other flag 29 extends down through and is vertically movable in this tube so that it may be 105 raised by a person in the boat in order to display the flag at an elevated position above the boat.

The boat, when arranged on a vessel, is supported on skids 30 the overhang bearing 110 on the skids. A vertical shaft 31 is mounted on a bearing 32 in the center of the bot-

tom of the boat and has an operating lever 33 at its upper end. A cross arm 34 is secured to the lower end of this shaft and arranged below the bottom of the boat are a 5 pair of locking bolts 35 which are movable radially under the bottom of the boat and have their inner ends pivotally connected as at 36 to the said cross arm at points near the ends of the latter. These locking bolts are 10 arranged to operate in guides 37 under the bottom of the boat and their outer ends are adapted to engage keepers 38 with which the skids are provided. The boat is normally locked to the skids by the bolts. When 15 the boat is to be used it may be detached from the skids by turning the shaft 31 so as to withdraw the bolts from the keepers as will be understood and this may be readily done by one man. A light but suffi- 20 ciently strong cable 39 is coiled around the top of the boat immediately above the overhang, one end of the cable is attached to the

boat as at 40 and an anchor 41 is attached to the other end of the cable. The anchor may be cast in order to prevent the boat from 25 drifting on rocks and foundering or breaking up.

Signal lanterns or other lights may be hung in the boat opposite the windows to indicate the position of the boat at night. 30

I claim:—

A circular life boat having a bottom of less diameter than the boat, an annular overhang around the bottom, a top rising from the overhang, and seats arranged radially on 35 the overhang, each seat having a hinged back adapted to be lowered outwardly and on and to be supported by the overhang.

In testimony whereof I affix my signature in presence of two witnesses.

VICTOR LINDBERG.
